UNITED STATES PATENT OFFICE.

CARL F. BRAUN, OF PASADENA, CALIFORNIA.

TESTING JIG AND METHOD OF USE.

Application filed February 7, 1923. Serial No. 617,491.

This invention relates to a method and means of testing the tubes of tubular apparatus, such as heat exchangers, condensers, tubular boilers, and the like.

It often occurs that a tube in a heat exchanger or like structure develops a leak, and it is desirable to quickly and accurately determine the leaky tube. The usual method of locating these leaky tubes is to shut off the fluid from inside the tubes and to remove the channel cover, thereby exposing one end of the tube. Fluid pressure is then created within the passages surrounding the tube nest, so that fluid will pass inwardly through any rupture which may exist in the wall of the separate tubes. When fluid drains from one end of the tubes it is assumed that the particular tube is leaking. This method is not certain, particularly when the floating head of the tube nest is lower than the other. In that event fluid from a leaky tube will flow into the passage in the floating channel and will pass back through the lowest tube, regardless of which tube is leaking. Uncertainty will also develop if the leak is in the tube sheet, either through the sheet or around a tube, in which event the leaking fluid will flow down the face of the tube sheet and back through the lowermost tube in the passage-way. It is the principal object of the present invention, therefore, to provide means whereby external fluid pressure may be simultaneously applied to all of the tubes in the nest, and any leaks which have developed in the tubes will be directly indicated by fluid flowing from the respective tube.

The present invention is particularly adapted for use in connection with heat exchangers provided with a tube nest having a floating head at one end, as disclosed, for example, in my copending application filed September 3, 1919, Serial No. 321,450, patented January 16, 1923, as Patent No. 1,442,783, and entitled Heat exchanger, the invention contemplating the use of jigs or fixtures by which the space around the floating head of the tube sheet may be packed to permit the application of external fluid pressure to all of the tubes within the shell, and to insure that the leaking fluid will drain out through the damaged tube.

The invention is illustrated by way of example in the accompanying drawing, in which the figure is a view in side elevation

showing a heat exchanger with parts broken for the sake of clearness, and disclosing the application of the present invention thereto.

Referring more particularly to the drawing, 10 indicates the shell of a heat exchanger, said shell being formed with body nozzles 11, said nozzles appearing arranged one above the other in the present drawing, but being designed to produce a circulation of fluid through the shell. 12 indicates a channel fitting adapted to be secured to the end of the shell adjacent the body nozzles. This fitting is provided with a pair of channel nozzles 13, which are shown as being positioned one above the other in the drawing, but which permit a circulation of a fluid through tubes 14. It is common practice to rigidly secure one tube sheet of the nest of tubes 14 between the end of the shell and the channel member 12. The opposite end of the tube nest is preferably free to float and is fitted with a cap or floating head 15 indicated by dotted lines in the drawing. A body cover 16 is secured over the end of the shell adjacent the floating head as indicated by dotted lines. The channel member 12 is normally closed at its outer end by a cap 17 indicated by dotted lines in the drawing.

The present invention is particularly concerned with means for sealing the end of the shell adjacent the floating tube sheet 24 and at the same time to disclose the opposite ends of all of the tubes. This is done by supplying a stuffing box ring of substantially the same diameter as the shell, and indicated at 18. This ring has a bolting flange by which it may be clamped to the bolting flange of the shell and thus secured by bolts 19.

Suitable packing gaskets 20 are interposed between the contiguous faces of the ring and the shell, the gasket being preferably mounted in an annular face groove on the ring. The body portion of the ring is cylindrical, its outer end being counterbored to form a shoulder 21 against which a gasket ring 22 may be seated. This ring will assume its normal position around the circumferential edge of the floating tube sheet 24. A stuffing gland 23 is adapted to project into the ring 18 and to be forced against the ring 22. The meeting faces of the stuffing gland and the packing ring 22 are obliquely inclined so that pressure exerted against the ring will deform it and cause it to pack around the circumferential

edge of the tube sheet 24 and thus prevent leakage of fluid from within the shell. Plugs 25 are also provided to close the holes through which the bolts of floating head 15 pass. The gland 23 is held in its tightened position by bolts 26 which are fastened in the end face of the stuffing ring 18 and are threaded at their outer ends to receive nuts 27. Tube sheet supporting means are provided to steady the tube sheet 24 when pressure is applied. This means comprises a screw 28 passing through a lug 29 carried by the gland 23. This screw is fitted with a swivel end 30 which rests against the face 15 of the tube sheet 24.

In operation of the present invention the heat exchanger is prepared for testing by removing the cap 17 at one end of the structure and the shell cover 16 at the opposite 20 end together with the floating head 15. After this has been done the bolt holes in the floating tube sheet 24 are closed by plugs 25. The stuffing ring 18 is then secured in position against the end face of the opened end 25 of the shell by bolts 19 and a tight joint made by the use of the packing ring 20. The rubber gasket 22 is then disposed around the circumferential edge of the tube sheet 24 and is forced into a packing position by the pressure of the gland 23 as it is drawn against the ring by tightening the bolts 26. When the rubber ring 22 has formed a tight joint around the tube sheet the set screw 28 may be tightened to bring 30 the end member 30 against the outer face of the tube sheet 24 and thus give it stability, at the same time preventing the fluid pressure within the shell from loosening the joints between the tubes and the sheet. After 35 the fixture has thus been applied to the heat exchanger or like structure, fluid pressure may be established within the shell by delivering a fluid under pressure through the nozzles 11, and in view of the fact that 40 the interior of the tubes will be under a con-

dition of atmospheric pressure the fluid from within the shell will readily leak through any holes or ruptures in any of the tubes. When this takes place the fluid will drain out from one or the other end of the 50 leaky tube. This may be instantly observed and the respective tube replaced.

It will thus be seen that by the use of the testing fixtures here disclosed it is possible to accurately locate leaking tubes in a tube 55 nest without removing the nest from its shell, and to permit the tubes thus located to be readily replaced.

While I have shown the preferred form 60 of my invention as now known to me, it will be understood that various changes might be made in the combination, construction, and arrangement of parts by those skilled in the art, without departing from the spirit 65 of the invention, as claimed.

Having thus described my invention, what I claim and desire to secure by Letters 70 Patent is:

A method of testing the tube nest of a 75 heat exchanger, which exchanger comprises an outer shell having a removable end, and within which shell the tube nest comprising tubes supported at one end in a tube sheet is disposed during the testing operation, said method consisting in first removing the 80 end of the shell to disclose the tube sheet, thereafter applying means forming a joint for the opening between the tube sheet and the shell wall and then creating a tight joint between said means and the tube sheet 85 and between the same and the wall of the shell, while permitting the open ends of the tubes projecting through the tube sheet to be disclosed, thereafter creating fluid pressure within the shell whereby said fluid will leak through the walls of the defective tubes, and thereafter drain from the disclosed ends of 90 said defective tubes.

CARL F. BRAUN.
